COIN CONTROLLED LOCK

Edwin E. Dougherty, Los Angeles, Calif.

Application September 26, 1930
Serial No. 484,665

5 Claims. (Cl. 194—74)

The present invention relates to improvements in coin controlled locks and has reference more particularly to certain improvements over the coin operated lock disclosed in my prior Patent 5 No. 1,560,146 issued November 3, 1925.

One of the important objects of the present invention is to provide a coin controlled lock that is used more particularly for preventing access to compartments, lavatories and the like, unless 10 the proper coin is deposited in the lock.

One of the salient objects of the present invention resides in the provision of means for indicating when the compartment with which the lock is associated is occupied or vacant.

Still a further object is to provide a coin controlled lock of the above mentioned character which is of such construction as to prevent the same from being picked or otherwise enabling unauthorized persons to obtain access to the 20 working parts of the lock.

A further and important object is to provide a coin controlled lock of the above mentioned character whereby access to the interior of the lock casing can be readily and easily had by any 25 authorized person, and this without necessitating the disassembly of the entire lock structure.

Still a further object is to provide a coin controlled lock of the above mentioned character which is simple in construction, inexpensive, 30 strong and durable and further well adapted to the purposes for which it is designed.

Other objects and advantages of the present invention will become apparent from the following description when taken in connection with 35 the accompanying drawing.

In the accompanying drawing wherein like reference characters indicate corresponding parts throughout the several views:

Figure 1 is a perspective view of my improved 40 coin controlled lock looking at the outer side;

Figure 2 is a detail perspective view showing the cover plate disposed over the lock mechanism with the inner and outer bolt spindles extending through the cover plate;

Figure 3 is a view somewhat similar to Figure 2 showing the cover plate removed and disclosing the position of the parts when a coin is deposited in the slot or recess provided therefor in the retractile bolt; and

Figure 4 is a further detail more clearly disclosing the sliding indicator forming a salient part of the present invention.

In the drawing, wherein for the purpose of illustration is shown the preferred embodiment of 55 my invention, the numeral 1 designates generally

the casing that is adapted to be secured on the outer side of a door to a compartment. The casing includes a rear wall 5 and a flanged front wall 20, the flange that extends around the edges of the front wall being disposed at an angle so 60 as to produce a bevelled edge around the front wall for the purposes of preventing the lock from being picked.

Mounted for slidable movement within the casing 1 is the horizontal retractile bolt 21, the nose 65 14 that is formed on the forward end thereof projecting through a suitable guide and being disposed through the bevelled side edge of the front wall 20.

The bolt 21 is mounted against the rear wall 70 5 in the same manner as specifically described in my prior patent and, therefore, a further detailed description and disclosure of this feature is believed unnecessary in the present case. The coin receiving recess formed in one side face of 75 the retractile bolt 21 is indicated at 25 and projecting upwardly through the top of the casing for communication with the coin receiving slot 25 is the coin delivery chute 26, the same being formed in its upper end with the coin receiving 80 opening 27 whereby the proper coin when deposited in said opening will by gravity pass downwardly through the chute 26 and will be deposited within the recess 25 of the bolt 21.

Co-operating with the inner end portion of 85 the retractile bolt 21 is the lever 9 that is fixedly secured on the rotatable spindle 19. This spindle is journalled through the rear wall 5 and the door on which the lock is secured and a door knob (not shown) is mounted on the inner end of this 90 spindle for actuating the lever from the inside of the compartment. The outer end of the spindle 19 projects through a cover plate 28 that is arranged in spaced relation with respect to the rear wall 5 for disposition within the casing. 95 Suitable laterally extending lugs 29 project outwardly from the rear wall 5 and are formed in their outer edges with threaded openings to accommodate securing screws 30 that hold the cover plate 28 in position. The outer end of 100 the spindle 19 also extends through the front wall 20 of the casing and is so constructed as to be engaged by the proper key for facilitating the actuation of the lever 9 from the outside whereby the bolt may be retracted without the insertion of a coin in the coin chute 26.

The manner in which the lever 9 co-operates with the bolt to retract the same has also been clearly defined in my prior patent.

In lieu of the axial coil spring employed in my 110

prior patent for holding the lever 9 in its normal inoperative position, I provide in the present instance the leaf spring 31 and the manner in which this leaf spring co-operates with the lever 5 is clearly illustrated in Figure 3 of the drawing.

The spindle on which the outside knob 15 is secured is indicated at 16 and this spindle extends through the front wall and the cover plates 20 and 28 respectively, and carried by the inner 10 end of this spindle 16 is the arm 17, the same carrying at its upper end, the laterally extending fingers 41 and 22 that are disposed above and below the retractile bolt 21. This unit of the lock is of substantially the same construction as the 15 unit disclosed in my prior patent and a leaf spring 32 co-operates with the movable arm 17 for holding the same in its normal position.

The lowermost finger 22 constitutes a rest on which the deposited coin lies while the upper 20 finger acts as an operating means for co-operation with the coin to effect the retraction of the bolt when the knob 15 is operated.

As clearly described in my prior patent, when the parts are arranged as shown in Figure 3, the 25 lock may be opened by actuating the knob 15 and this will result in the lever 17 swinging in an inward direction so that the finger 41 will push the coin against the remote shoulder of the recess 25 so that the coin acts as a connecting 30 means between the lever and the bolt whereby the bolt may be retracted.

Of course, when a coin is not deposited in the 35 opening 27, the lock cannot be opened from the outside unless a proper key engages the projecting outer end of the spindle 19. The key engaging means may be in the form of a lug 13.

One of the improvements over my prior patent 40 comprises an indicator for association with the lock whereby to indicate when the compartment is occupied or vacant and to this end, there is provided within the upper portion of the casing 1, the horizontal sliding plate 33 operable between suitable guides arranged within the casing. On the front face of this plate 33, there is 45 inscribed or otherwise arranged the words "Occupied" and "Vacant". A sight opening 5 is formed in the front wall of the casing to display either of the indicating words.

A pin 11 projects laterally from the rear wall 50 of the plate 33 and is disposed within the path of movement of the pivoted lever 6 and this lever is in turn provided with a projection 7 at its pivoted end that is disposed within the path of movement of the coin resting in the recess 25. It is readily obvious that when the coin moves 55 inwardly with the bolt, said coin will operate the projection 7 to swing the lever 6 in one direction and this lever will co-operate with the pin 11 to effect the actuation of the plate 33 so that the word "Occupied" will be displayed to view 60 through the opening.

When the door is opened from the inside, the 65 lever 9 will actuate the pivoted trip 10 to release the projected indicator slide plate 33 and the spring 34 will retract the plate so that the word "Vacant" will be displayed through the opening 5. The trip or trigger 10 holds the slide plate 33 in place when the latter is in "in use" position. The lobes formed on the trip or trigger 10 act as 70 a balance to throw the trigger end of the trip 10 into the notch formed in the plate 33 when the indicator slide plate is pushed back to the "in use" position. This trip or trigger 10 is mounted in such a manner as to be disposed in coacting 75 relation with respect to the lever 9 so that when

the inside knob is turned, the trigger or trip will be actuated by the lever to release the trigger end of the trip from the notch in the indicator slide plate 33 and the coil spring 34 will pull the indicator slide plate back to the "vacant" position. A 80 counter weight 8 co-operates with the pivoted lever 6 for returning the same to its initial position thus resetting the parts of the indicating mechanism so that said indicating mechanism will be positively operated.

As also explained very clearly in my prior patent, when the inside knob is actuated, the bolt will be retracted without effecting the movement of the arm 17 and the fingers 21 and 22 so that the coin resting in the recess 25 will drop into the 90 bottom of the casing and the coins may be removed from the casing in the manner as proposed in my prior patent. Access may also be had to the interior of the casing and to the working parts of the lock in a similar manner.

It will thus be seen from the foregoing description, that I have provided a coin controlled lock that will at all times be positive and efficient in its operation and due to its simplicity, the same can be constructed at a very low cost. Also the 100 provision of an indicating mechanism in association with the lock will enable persons to readily ascertain whether they can obtain access to the interior of the compartment without the loss of a coin. Furthermore, the construction of the 105 casing is such as to preclude the possibilities of the lock being picked.

While I have shown the preferred embodiment of the invention, it is to be understood that minor changes in the size, shape and arrangement of 110 parts may be resorted to without departing from the spirit of the invention and the scope of the appended claims.

Having thus described the invention, what I claim is:

1. A coin controlled lock comprising in combination, a casing, a retractile bolt mounted in the casing, and provided with a coin receiving recess, a coin chute for delivering a coin deposited in the lock to said recess, means for co-operation with the coin in the recess to retract the bolt, a normally inoperative signal associated with the casing operable by the coin in the recess in the bolt for moving said signal to an operative position when the bolt 125 is retracted, and spring controlled means for releasing and returning the signal to its normal position when the bolt is again retracted.

2. A coin controlled lock comprising in combination, a casing adapted to be mounted on a door 130 of a compartment, a retractile bolt mounted in the casing and normally projecting through one side thereof, said bolt being provided with a coin receiving recess, a coin chute for delivering a coin deposited in the lock to said recess, a lever operable from the inside of the compartment for retracting the bolt, an arm operable from the outside of the compartment, coin engaging fingers extending laterally from said arm for disposition above and below the bolt, a signal for indicating 135 when the compartment is occupied associated with the casing, means for moving the signal to an operative position and operable by the coin deposited in said recess during the retractile movement of the bolt, and additional means operable 140 by said lever for releasing and returning the signal to its normal inoperative position when the bolt is again retracted.

3. A coin controlled lock comprising in combination, a casing adapted to be mounted on a door 150

of a compartment, a retractile bolt mounted in the casing and normally projecting through one side thereof, said bolt being provided with a coin receiving recess, a coin chute for delivering a coin deposited in the lock to said recess, a lever operable from the inside of the compartment for retracting the bolt, an arm operable from the outside of the compartment, coin engaging fingers extending laterally from said arm for disposition above and below the bolt, a signal for indicating when the compartment is occupied associated with the casing means for moving the signal to an operative position and operable by the coin deposited in said recess during the retractile movement of the bolt, said signal including a plate arranged for slidable movement in the casing, the casing being provided with an opening through which the plate is viewed, a pin projecting laterally from the plate, a pivoted lever mounted in the casing for co-operation with said pin, and a projection formed on the pivoted end of the lever disposed within the path of movement of the coin resting in the recess and means for moving the indicator plate to its normal inoperative position when the bolt is released from the inside of the compartment, said last mentioned means including a pivoted trip arranged within the casing for engagement with the slidable plate, said trip being disposed in the path of movement of the first mentioned lever, and a retractile spring connecting the slidable plate with the casing.

10 above and below the bolt, a signal for indicating when the compartment is occupied associated with the casing means for moving the signal to an operative position and operable by the coin deposited in said recess during the retractile movement of the bolt, said signal including a plate arranged for slidable movement in the casing, the casing being provided with an opening through which the plate is viewed, a pin projecting laterally from the plate, a pivoted lever mounted in the casing for co-operation with said pin, and a projection formed on the pivoted end of the lever disposed within the path of movement of the coin resting in the recess and means for moving the indicator plate to its normal inoperative position when the bolt is released from the inside of the compartment, said last mentioned means including a pivoted trip arranged within the casing for engagement with the slidable plate, said trip being disposed in the path of movement of the first mentioned lever, and a retractile spring connecting the slidable plate with the casing.

15 5. A coin controlled lock comprising in combination, a casing adapted to be mounted on a door of a compartment, a retractile bolt mounted in the casing and normally projecting through one side thereof, said bolt being provided with a coin receiving recess, a coin chute for delivering a coin deposited in the lock to said recess, a lever operable from the inside of the compartment for retracting the bolt, an arm operable from the outside of the compartment, coin engaging fingers extending laterally from said arm for disposition above and below the bolt, and a signal for indicating when the compartment is occupied associated with the casing and operable by the coin deposited in said recess during the retractile

movement of the bolt, said signal including a plate arranged for slidable movement in the casing, the casing being provided with an opening through which the plate is viewed, a pin projecting laterally from the plate, a pivoted lever mounted in the casing for co-operation with said pin, and a projection formed on the pivoted end of the lever disposed within the path of movement of the coin resting in the recess and means for moving the indicator plate to its normal inoperative position when the bolt is released from the inside of the compartment, said last mentioned means including a pivoted trip arranged within the casing for engagement with the slidable plate, said trip being disposed in the path of movement of the first mentioned lever, and a retractile spring connecting the slidable plate with the casing.

20 6. A coin controlled lock comprising in combination, a casing, a retractile bolt mounted in the casing and provided with a coin receiving recess, a coin chute for delivering a coin deposited in the lock to said recess, means for cooperation with the coin in the recess to retract the bolt, a horizontal sliding indicator plate arranged in the casing and normally disposed in an inoperative position, a laterally extending pin carried by said indicator plate, a pivoted lever mounted in the casing for engagement with said pin, a projection formed on the pivoted end of the lever disposed within the path of movement of the coin resting in the recess, said lever cooperating with the pin to move the indicator plate to an operative position when the bolt is retracted, a counterweight associated with the pivoted lever for returning the same to its normal position, a coil spring associated with the slidable indicator plate and the casing for returning said indicator plate to its normal inoperative position, and a releasable trip member mounted in the casing for holding the slidable indicator plate in its operative position.
